The ornamental design for a pneumatic tire, as shown and described.

DESCRIPTION

FIG. 1 is an end elevational view of one end of a pneumatic tire showing my new design;

FIG. 2 is an end elevational view of the opposite end of the pneumatic tire shown in FIG. 1;

FIG. 3 is a side elevational view of one side of the pneumatic tire shown in FIG. 1;

FIG. 4 is a side elevational view of the opposite side of the pneumatic tire shown in FIG. 1; and,

FIG. 5 is a perspective view of one side of the pneumatic tire shown in FIG. 1.

In the drawings, the broken lines show the sidewall of a pneumatic tire only and form no part of the claimed design.
